UNITED STATES PATENT OFFICE.

SEWARD H. SKINNER, OF CALWA, CALIFORNIA.

CAN PERFORATOR.

Application filed April 3, 1928. Serial No. 267,013.

This invention relates to devices for perforating condensed milk cans and the like, and particularly represents modifications and improvements shown in my co-pending application for Patent Serial No. 257,603, filed February 28th, 1928.

In the previous device it was necessary to press against the handle provided on one end of the perforator to cause one of the prongs 10 or punches to be withdrawn from its opening in the can to enable the contents thereof to be poured out.

The principal object of the present invention is to avoid the need of thus manually 15 manipulating the device after it is once in position relative to the can, by constructing the same so that when the can is tipped in a certain direction one of the prongs will automatically move clear of its opening, so that 20 the contents of the can may be then poured out without interference of the prong. At the same time when the can is restored to its normal upright position the prong previously clear of its opening will again and automatically move to a closed position in said 25 opening.

A further object of the invention is to produce a simple and inexpensive device and yet one which will be exceedingly effective for the 30 purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a sectional elevation of a can showing my improved perforator in the position occupied when the can is upright.

Fig. 2 is a sectional elevation of the can tilted showing the position of the perforator relative thereto.

Fig. 3 is a perspective elevation of the perforator detached.

Referring now more particularly to the characters of reference on the drawings, the numeral 1 denotes a relatively long rigid and flat vertical arm with parallel side edges. 50 This arm is sharpened on its lower end as at 1^a so as to form a prong to readily puncture the top of the can 2.

The upper end of this arm is connected to or formed integral with a rigid horizontal 55 bar 3 which is formed adjacent its end opposite the arm 1 with a flat and preferably

rounded pad 4. A short prong 5 depends from the outer end of the pad, and is spaced horizontally from the arm 1 a lesser distance than the diameter of the can.

The outer edges of the members 1 and 3 adjacent their junction are beveled off as at 6 so that the diagonal width A of the implement at that point is less than the width of the arm 1 and consequently of the opening made 60 thereby. A short distance from the inner edge of the arm 1 is a short lug 7 which depends from the member 3 to form a recess 8 between said arm and lug; the direct distance from the bottom of the lug to the beveled edge 6 being not less than the width of the arm 1, and consequently of the opening 9 made in 65 the can by said arm.

In operation the implement is disposed on 75 the can so that the member 3 extends diametrically thereof and the arm is first pressed down into the top of the can to form the opening and until the lug 7 bears against the top. Pressure is then exerted on the pad 4 to cause 80 the prong 5 to also puncture the can top adjacent its opposite side to form the pouring or dispensing opening 10. The arm is sufficiently long to extend nearly to the bottom 85 of the can and this length with the accompanying weight is sufficient to cause the arm 90 to act as a pendulum or counterweight, tending to maintain the member 3 in the same horizontal position even when the can is tilted so that the contents will be dispensed from the opening 10. As a result of this arrangement and construction therefore, the prong 95 5 will clear the opening 10 when the can is thus tilted, and the contents of said can may be dispensed therefrom without interference with said prong, the device as a whole rocking on the lug 7 as an axis.

Since the arm 1 is flat it cannot turn in the can and when the latter is restored to its normal upright position the prong 5 will again of itself enter and close the opening 10.

The beveled edge 6 of the device not only 100 enables this rocking movement to take place without causing the arm 1 to wedge in the opening, but causes a portion of such opening to be partly unoccupied when the can is tilted, so as to provide the necessary air vent when dispensing from the opening 10. The metal at the opposite end of the opening 9 then enters the recess 8, and the lug prevents the bar 3 from possibly slipping down 105 through the opening 9, which would dislodge the structure from its natural position and

prevent the proper reentering of the prong 5 into its opening when the can was returned to its upright position.

From the foregoing description it will be 5 readily seen that I have produced such a device as substantially fulfills the objects of the invention as set forth herein.

While this specification sets forth in detail 10 the present and preferred construction of the device, still in practice such deviations from such detail may be resorted to as do not form a departure from the spirit of the invention, as defined by the appended claims.

Having thus described my invention what 15 I claim as new and useful and desire to secure by Letters Patent is:

1. A can perforator comprising a relatively long prong-arm to be depressed through the top of a can and to then depend 20 into the can, a short prong to be depressed into the can at a point opposite to the opening made by the arm, and a rigid member connecting said arm and prong; said rigid member terminating at and sloping down to 25 the edge of the arm opposite to the prong.

2. A structure as in claim 1, with a lug formed on said connecting means adjacent the arm to rest on top of the can and form a bearing about which the device may rock.

3. A can perforator comprising a relatively long prong-arm to be depressed through the top of a can and to then depend 30

into the can, a short prong to be depressed into the can at a point opposite to the opening made by the arm, and a rigid member 35 connecting said arm and prong, the length and weight of the arm being such that it will tend to remain in a vertical position when the can is tilted in one direction.

4. A can perforator comprising a relatively long prong-arm to be depressed through the top of a can and to then depend 40 into the can, a short prong to be depressed into the can at a point opposite to the opening made by the arm, and a rigid member 45 connecting said arm and prong, the length and weight of the arm being such that it will tend to remain in a vertical position when the can is tilted in one direction, and means formed with the device for enabling the same 50 to rock relative to the can when the latter is thus tilted.

5. A can perforator comprising a rigid member to extend across the top of a can, prongs depending from the ends of said 55 member, and means formed with one of said prongs for exerting a pendulum action tending to maintain said member horizontal when the can is tilted whereby to cause the other prong to be moved out of its incision in the 60 can.

In testimony whereof I affix my signature.

SEWARD H. SKINNER.
